(57) **CLAIM**

The ornamental design for a placket with an inverse fastener, as shown and described.

DESCRIPTION

This application contains at least one drawing executed in color. Copies of this application with color drawing(s) will be provided by the Office upon request and payment of the necessary fee.

FIG. 1 is a front view of an outer portion of a placket with an inverse fastener showing my new design, wherein the placket is closed;

FIG. 2 is a rear view of the outer portion or a front view of an inner portion of the placket of FIG. 1, wherein the placket is open;

FIG. 3 is a rear view of the outer portion or a front view of the inner portion of the placket of FIG. 1, wherein the placket is closed;

FIG. 4 is a first side view of a portion of FIG. 2;

FIG. 5 is a second side view of a portion of FIG. 2;

FIG. 6 is a top view of FIG. 4;

FIG. 7 is a top view of FIG. 5;

FIG. 8 is an enlarged view of the inverse fastener in FIG. 2; and,

FIG. 9 is an enlarged view of the inverse fastener in FIG. 3. The short-dash broken lines form no part of the claimed design. The claimed design extends to the long-dash broken line boundaries in FIGS. 2, 3, 5, 7, 8, and 9, but does not include the boundary.

No claim is made to the thickness of the inverse fastener or the color of the inverse fastener apart from the red front surface of the inverse fastener.
